C. J. ROTHERMEL.
SEAL.
APPLICATION FILED JAN. 6, 1917.

Patented Dec. 30, 1919.

Curtis J. Rothermel. INVENTOR
BY Heidersheim & Fairbanks.

ATTORNEYS

UNITED STATES PATENT OFFICE.

CURTIS J. ROTHERMEL, OF PHILADELPHIA, PENNSYLVANIA.

SEAL.

1,326,291.

Specification of Letters Patent. Patented Dec. 30, 1919.

Application filed January 6, 1917. Serial No. 140,922.

To all whom it may concern:

Be it known that I, CURTIS J. ROTHERMEL, a citizen of the United States, residing in the city and county of Philadelphia, State of Pennsylvania, have invented a new and useful Seal, of which the following is a specification.

My invention relates to a novel construction of a seal or device for sealing railway cars, rooms, baggage, packages, and receptacles of any character, it being especially designed for use upon freight cars, where it is desirable to seal the car doors to prevent any removal or tampering of the goods contained therein, provision being made for enabling the shackle and head constituting my novel device to be readily assembled without the employment of tools, so that rupture or breaking of the seal is requisite for the car door, baggage, room, package or other receptacle to be opened, whereby any interference with the seal may be readily discerned upon inspection thereof.

To the above ends, my invention consists of a flexible metal strap or shackle having a novel configuration at the ends thereof, which latter are adapted to interlock or coact with a novel construction of head, so that a simple and novel seal is produced which may be locked without the use of tools or extraneous devices, and which cannot be unlocked without being destroyed.

For the purpose of illustrating my invention, I have shown in the accompanying drawing one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a seal for car or other doors, baggage, packages, receptacles or the like, embodying my invention, the parts being shown in detached position.

Fig. 2 represents a sectional view showing the initial step employed in assembling the shackle and head.

Fig. 3 represents a longitudinal, sectional view showing the shackle and head in assembled position.

Fig. 4 represents another view of the parts seen in Fig. 3 in slightly different position.

Similar numerals of reference indicate corresponding parts in the figures.

Referring to the drawings:—

1 designates my novel construction of seal, the same comprising the head member 2 and the shackle member 3.

In the preferred embodiment of my invention, the head 2 is composed of a body portion preferably formed in one piece and having the top wall or member 4, the bottom wall or member 5, and the converging side walls 6, said side walls terminating in the inwardly turned lips 7, between which a space is left for the insertion of the locking terminals or ends of the shackle member 3.

The shackle 3, as will be understood from the right-hand portion of Fig. 1, comprises a strip of thin sheet metal bent to form the resilient members 8, each of which is provided with the outwardly extending flange 9, which is doubled upon itself, as indicated at 10, thereby forming an abutment and then continued as indicated at 11, the terminals 80 of the members 8 of the shackle being deflected outwardly (or diverging), as indicated at 12, whereby locking tongues are formed, which can be readily inserted within the converging walls 6 of the head 2.

The manner of assembling the seal will be apparent from Fig. 2, one of the tongues 12 being first inserted within the head 2 and being prevented from withdrawal therefrom by its engagement or interlocking 90 with the contiguous inwardly turned lip 7.

The other terminal 12 is next inserted in position, as will be understood from Figs. 2 and 3, and when said terminals 12 are in the position indicated in said Fig. 3, 95 it will be apparent that by reason of the resiliency of the thin metal strips employed both of said terminals 12 will spring slightly outwardly and so be prevented from withdrawal or dislodgment by reason of their 100 interlocking or engagement with the inwardly deflected lips or flanges 7, as will be understood from Fig. 3, there being a slight play permitted for the terminals 12 in respect of the flanges 7, as will be understood from Fig. 4, wherein it will be seen that the members 10 act as shoulders or abutments, limiting the inward movement of the shackle 3 with respect to the head 2, while the engagement of the ter- 110

- minals 12 with respect to the inwardly turned flanges 7 will prevent the disconnecting of the shackle and head without the destruction or breaking of the device, it 5 being apparent that any improper tampering or interference with the seal after the head and shackle have been interlocked or assembled, can be at once discovered upon inspection thereof.
- 10 By reason of the convergence of the side walls 6 and the resiliency of the diverging terminals 12, it will be apparent that the latter will contact at all times with the inner surface of said side walls and thus engage the lips 7, if any pull is exerted on the shackle 3.

I am aware that it has heretofore been proposed to form tongues near the end of a shackle, but such tongues present a limited 20 area of locking surface and are not so efficient in performing their locking functions as are my deflected terminals 12.

It will be further apparent that by reason of my novel construction, after the parts 25 are assembled as seen in Figs. 3 and 4, the lock formed thereby cannot be readily picked or tampered with.

The head 2, as well as the shackle 3, can be readily struck up, pressed or stamped 30 from thin sheet metal by means of suitable dies or other implements, and can be cheaply manufactured in large quantities, and the head and shackle can be readily assembled manually without the use of tools or other 35 extraneous devices, as will be apparent to those skilled in the art.

It will be apparent that in case anyone attempts to pick the lock and to move the strip 8 rearwardly from the position seen 40 in Fig. 4, the locking tongues 12 will engage the inwardly turned lip 7 so that it will be impossible to pry down one of the locking tongues 12 and remove it from the head 2, so that the abutment is in such 45 position with respect to the head that when

the tongues 12 and lips 7 are not interlocked, it will be impossible to insert an implement to bend the tongues 12, so that they can be removed from the head 2. It will thus be seen that in order to unlock the device, it 50 will be absolutely necessary to break and destroy it.

It will now be apparent that I have devised a novel and useful seal, which embodies the features of advantage enumerated 55 as desirable in the statement of the invention and the above description, and while I have, in the present instance, shown and described a preferred embodiment thereof which will give in practice satisfactory and 60 reliable results, it is to be understood that the same is susceptible of modification in various particulars without departing from the spirit or scope of the invention or sacrificing any of its advantages.

Having thus described my invention, what I claim as new and desire to secure by Letters Patent, is:—

In a seal, the combination with a head composed of top, bottom, and converging 70 side walls and inwardly turned lips, of a shackle comprising a strip having each of its free ends rearwardly deflected and diverging to form spring tongues to interlock with said lips upon the inserting of said 75 tongues into said head, said strip in proximity to said tongues having abutments formed by doubling the strip upon itself, said abutments being adapted to contact with said head when the tongues are moved 80 thereinto sufficient to clear said lips, and prevent the insertion of a tool into said casing to press the free end of a tongue toward its strip to permit it to pass by the lip with which it interlocks.

CURTIS J. ROTHERMEL.
